OSCILLATING FAN

Gustav H. Koch, Springfield, Mass., assignor to
Westinghouse Electric & Manufacturing Com-
pany, East Pittsburgh, Pa., a corporation of
Pennsylvania

Application May 25, 1937, Serial No. 144,631

9 Claims. (Cl. 230—256)

My invention relates to oscillating fans and more particularly to the method of driving the oscillating mechanism of such fans.

An object of my invention is to provide an inexpensive flexible coupling between the motor and oscillating mechanism which will be efficient and silent in the operation thereof.

A further object of my invention is to provide a motor resiliently mounted within a housing and flexibly coupled with the oscillating mechanism so that the vibrations of such motor cannot be transmitted to the housing, fan support, or oscillating mechanism.

A further object of my invention is to provide a housing which may enclose and support the oscillating mechanism, flexible coupling and driving motor, and which will be modern and artistic in general outward appearance.

Other objects of my invention will be either pointed out specifically in the course of the following description of a device embodying my invention or will be apparent from such description.

In the accompanying drawing:

Figure 1 is a partial elevational and sectional view of a device embodying my invention;

Fig. 2 is a partial plan view of the device shown in Fig. 1 and,

Fig. 3 is a sectional view taken along the line III—III of Fig. 1.

Referring to the accompanying drawing, I show a fan housing 11, a motor 15 resiliently mounted therein, an oscillating mechanism 25, and a flexible coupling device 35 operatively associated with the motor 15 and the oscillating mechanism 25.

The housing 11 may be substantially ellipsoidal in shape as shown, and may comprise a removable upper section 12 and a stationary bottom section 13. The upper section 12 may be rigidly attached to the bottom section 13 in any suitable manner (not shown).

The motor 15 may be of any type desired and may be resiliently attached to the lower portion 13 of the housing 11 and located therein. The motor 15 may have a rotor shaft 19, one end 21 of which may extend outside the motor housing, and upon which the fan blades may be attached. The other end of rotor shaft 19 may be located within the housing 11 and may have a threaded aperture 20 within the end thereof. The motor 15 may be resiliently and rotatably mounted at one end by a pedestal 17 and cap 18, and along the bottom portion thereof by means of suitable resilient mounting bushings 16 which may be of rubber.

The oscillating mechanism 25 is located within

the housing 11 and it is preferred to have the housing therefor attached to the lower portion 13. Such oscillating mechanism 25 comprises an adjusting knob 26, an oscillating crank 27, drive shaft 28, and suitable gearing 29 to change the horizontal rotational energy of shaft 28 to the vertical rotational energy of oscillating crank 27. The gears 29 may be located within a well 33, which may have a removable plate 34 rigidly attached to the top thereof. The crank 27 is provided with a crank pin 27' that is connected to a connecting rod 27a, the latter being pivotally carried by a suitable stationary portion of the fan structure such as, for example, a bracket 27b. As is well understood, the fan motor housing 11 is pivotally carried by the bracket so that it may oscillate.

The flexible coupling 35 may comprise a ventilating fan 30, a link 39 swingably attached thereto and a crank 36 operatively associated with the motor 15 and rotatably associated with the link 39. The ventilating fan 30 may be rigidly attached to drive shaft 28 by means of a set screw 31 and may have a plurality of fins or blades 32 located upon one surface substantially close to the periphery thereof and an aperture 41 located therein. The link 39 may be composed of any suitable material; however, it is preferred that such link be composed of a fibrous material or of leather. The link 39 may be swingably attached to the plane surface of ventilating fan 30 by means of a suitable rivet 40. The crank 36 may have one leg 37 thereof threaded to cooperate with the threaded aperture 20 of the motor 19. The other leg 38 of crank 36 may be inserted through the aperture 41 located within ventilating fan 30 and may be rotatably attached to the free end of link 39 in any suitable manner. It is, therefore, obvious that as the crank 36 is rotated about the leg 37 as an axis, leg 38 will pull link 39, and due to such link being rotatably attached to leg 38 and swingably attached to ventilating fan 30, it will cause the ventilating fan 30 to rotate with shaft 28 about the axis thereof. Due to the leg 38 of the crank 36 being inserted through aperture 41 and rotatably associated with link 39, it is obvious that such leg and the operatively associated link 39 may move relative to the ventilating fan 30.

In operating a device as hereinabove described, the motor 15 may be connected to the power supply by any suitable switching device (not shown). As the rotor shaft 19 in motor 15 begins to rotate, the stator of the motor 15 will move or vibrate in relation to the shaft 28 of the oscillating mecha-

nism 25 and the housing 11. However, due to the flexible coupling 35 being interposed between and operatively associated with rotor shaft 19 and shaft 28 and the presence of the resilient bushings 16 between the motor 15 and housing 11, the relative movement of the motor 15 will not be transmitted to the oscillating mechanism 25 or housing 11.

As the rotor shaft 19 rotates, crank 36 which is operatively associated therewith, likewise rotates about such shaft as an axis. Since the leg 38 of crank 36 is operatively associated with link 39 and ventilating fan 30, such ventilating fan will likewise rotate. However, since the leg 38 and the free end of link 39 operatively associated therewith may move relative to the ventilating fan 30, the relative transverse and longitudinal movements of the motor 15, rotor shaft 19 and leg 37 of crank 36 will not be transmitted to the ventilating fan 30. It is, therefore, to be understood that, regardless of the relative movement of the leg 38 of crank 36 in respect of the fan 30, such leg, through link 39 and rivet 40, will transmit the rotational energy of the rotor shaft 19 of motor 15 to the ventilating fan 30 and operatively associated oscillating mechanism 25 void of all vibrations or undesirable movements of such motor and crank. The rotational energy of fan 30 is then transmitted to the oscillating crank 27 through the operatively associated gears 29 where such energy may be used to oscillate the fan housing in any pre-described fashion, free from all the undesirable movements of the motor and crank.

It is, therefore, obvious that the resiliently mounted motor will operate any desirable fan located upon the shaft end 21 and will oscillate such fan and the housing in a pre-described orbit without transmitting the operating vibrations thereof directly to the housing 11 and the suitable support therefor or to the oscillating mechanism 25 and oscillating crank 27. It is likewise obvious that, due to such resilient mounting of the motor 15 within the housing 11 and the presence of link 39 between the crank and the oscillating mechanism, such device will be silent in the operation thereof.

Various modifications may be made in the device embodying my invention without departing from the spirit and scope thereof, and I desire that only such limitations shall be placed thereon as are imposed by the prior art and the appended claims.

I claim as my invention:

1. In combination, a housing, a motor resiliently mounted therein and an oscillating mechanism fixed thereto, and means comprising a crank enclosed by the housing for flexibly coupling the motor to said oscillating mechanism, said resilient mounting and flexible coupling serving to prevent transmission of motor vibrations to said mechanism.

2. In combination, a housing, a motor resiliently mounted therein, an oscillating mechanism comprising a ventilating fan attached to and located within said housing, and means comprising a crank and the ventilating fan for flexibly coupling the motor to said oscillating mechanism.

3. In combination, a housing, a motor resiliently mounted therein, an oscillating mechanism attached to and located within said housing, and means comprising a crank and a fibrous link for flexibly coupling the motor to said oscillating mechanism.

4. In combination, a housing, a motor resiliently mounted therein, an oscillating mechanism comprising a ventilating fan and a fibrous link swingably mounted thereon, and means comprising the ventilating fan, fibrous link and a crank operatively associated with the motor and rotatably attached to said link for flexibly coupling the motor to said oscillating mechanism.

5. An oscillating fan-driving mechanism comprising a housing, a motor resiliently mounted within the housing having a rotor shaft one end of which terminates within the housing, a threaded aperture located therein, a threaded crank operatively associated therewith, an oscillating mechanism including a ventilating fan, a link swingably attached to said fan and rotatably attached to the free end of said crank, and means including said crank, link and ventilating fan for flexibly coupling the motor to said oscillating mechanism.

6. An oscillating fan-driving mechanism comprising a housing having an upper and lower section, a motor resiliently mounted within the lower section of the housing having a rotor shaft one end of which terminates within the housing, a threaded aperture located therein, a threaded crank operatively associated therewith, an oscillating mechanism including a ventilating fan, a link swingably attached to said fan and rotatably attached to the free end of said crank, means including said crank, link and ventilating fan for flexibly coupling the motor to said oscillating mechanism, and means including the upper section of said housing for enclosing the motor, oscillating mechanism and coupling means.

7. An oscillating fan-driving mechanism comprising a housing having an upper and lower section, a motor resiliently mounted within the lower section of the housing having a rotor shaft one end of which terminates within the housing, a threaded aperture located therein, a threaded crank operatively associated therewith, an oscillating mechanism including a drive shaft, the axis of which is substantially in line with the axis of the rotor, a ventilating fan removably attached to said shaft, a link swingably attached to said fan and rotatably attached to the free end of said crank, means including said crank, link and ventilating fan for flexibly coupling the motor to said oscillating mechanism, and means including the upper section of said housing for enclosing the motor, oscillating mechanism and coupling means.

8. In combination, a motor having a housing therefor, means for resiliently supporting the motor within the housing, an oscillating mechanism including a ventilating fan attached to said housing, and means comprising a structure rotatable with the motor shaft and said fan for flexibly coupling said motor to said oscillating mechanism, said last-mentioned means being enclosed by the housing and preventing the transmission of vibrations between the motor and the oscillating mechanism.

9. In combination, a housing, a motor resiliently carried by the housing and having a rotatable shaft, a fan carried by the motor shaft, means for oscillating the motor and fan, said oscillating means including a driven shaft, and means including a crank interposed between said shafts for effecting a driving connection therebetween, whereby shifting of the axes of one shaft relative to the other shaft is afforded.

GUSTAV H. KOCH.
